(57) **CLAIM**

The ornamental design for a hot water tank repair tool, as shown and described.

DESCRIPTION

FIG. 1 is a front perspective view of a hot water tank repair tool in a slanted position, showing our new design;

FIG. 2 is a front elevation view of the hot water tank repair tool of FIG. 1 in an upright position;

FIG. 3 is a rear elevation view thereof;

FIG. 4 is a right side view thereof;

FIG. 5 a left side view thereof;

FIG. 6 is a top plan view thereof; and,

FIG. 7 is a bottom plan view thereof.
